(57) **CLAIM**

I claim the ornamental design for a snow board display rack,
as shown.

DESCRIPTION

FIG. 1 is a front perspective view showing my new design
of my snow board display rack,

FIG. 2 is a left side elevational view of my snow board
display rack; and,

FIG. 3 is a right side elevational view of my snow board
display rack.

1 Claim, 2 Drawing Sheets

FIG. 1
